UNITED STATES PATENT OFFICE

HENRY P. PINKHAM, OF WOLLASTON MASSACHUSETTS, ASSIGNOR TO CONDIT ELECTRICAL MANUFACTURING CORPORATION, OF SOUTH BOSTON, MASSACHUSETTS, A CORPORATION OF MASSACHUSETTS

MANUALLY OPERATED ELECTRIC SWITCH AND SWITCH MECHANISM

Application filed May 7, 1930. Serial No. 450,484.

This invention relates to electric switches for the control of small power circuits, as the circuits of electric motors, and particularly to switches having manually controlled means for operating them.

It is an object of the invention to provide improved mechanism for connecting the movable switch member and manual operating means which is simple and inexpensive to manufacture and assemble.

A further object of the invention is to provide simple and effective manually controlled switch operating mechanism for a multi-break electric switch.

A still further object of the invention is generally to improve the construction and operation of electric switches.

Fig. 1 is a side elevation of an electric switch embodying the invention, the enclosing casing being shown in section.

Fig. 2 is a front elevation of the switch of Fig. 1 with part of the casing broken away.

Fig. 3 is a perspective view of the manually controlled operating mechanism for the switch.

Fig. 4 is a detail of a toggle link.

Fig. 5 is a detailed view showing the connection between the operating mechanism and movable switch member.

The switch herein shown is contained within an enclosing casing having the fixed back part or section 10, open at the front, and the front part or section 12, which is hinged at its top edge to and constitutes a cover for the open front of said back part. The two parts of the casing are releasably connected together by a latch plate 14 carried by the back part 10 and extended forwardly through and arranged to engage the cover 12.

The switch includes the left and right hand side plates 16 and 18 which are provided with pairs of inwardly directed reflexed ears 20 at the top upon which the horizontal insulating plate 22 rests and to which it is rigidly secured by screws 24. Said side

plates are also provided with inwardly directed reflected flanges 26 at their lower front edges upon which the vertical insulating panel 28 rests and to which it is secured rigidly by screws 30 at the top and bottom thereof. The insulating plate 20 and the panel 28 thus constitute means for connecting the side plates rigidly together in spaced relation. Said side plates are also held in spaced relation by a transverse rod 29 having reduced end portions 29a which are received in and extended through suitable passages in said plates and which are struck over at their extended ends whereby to hold said side plates fixedly against the shoulders formed by said reduced portions 29a. Said side plates are also formed at the bottom rear edges thereof with outwardly reflexed flanges 32 which are provided at their upper ends with holes 34 having elongated passages to receive the outstanding heads of suitable rivets 36 fixed to the rear wall of said casing. Similar holes 38 are provided at the lower ends of said flanges to receive screws 40 by which the switch is secured removably to the casing.

The upper horizontal insulating plate 22 constitutes the carrier for and insulates a plurality of stationary contact members of which three sets are shown, one for each phase of the switch. A set includes three aligned contact members 42, 42a, and 42b each having a pair of contact faces 44. The end contact members are provided with upstanding ears 46 provided with wire clamping screws, which ears constitute the line terminals of the switch.

The movable switch member includes a horizontal insulating plate 48 which provides an insulating support for three sets of resiliently supported movable contact members which are aligned with and are arranged separately to bridge the sets of stationary contact members of the several phases, whereby

to provide four simultaneous breaks in series in each phase.

Said movable plate 48 is supported for vertical movement between said side plates 16 and 18 in a generally U-shaped frame 50 including the bottom plate 52 and the parallel reflexed upstanding side plates 54. Said side plates are further reflexed at their upper ends to provide inwardly directed flanges 56 which lie parallel with the bottom plate 52 of said frame and which are adapted to be received in horizontal grooves 58 formed in the sides of said movable contact plate 48, in which position said plate is releasably secured by a leaf spring 59 which is secured to said frame and which engages a notch 59a in the bottom face of said plate. Said frame is guided in its vertical movement by pairs of inwardly reflexed parallel ears 60 of said side plates which are received in suitable vertical kerfs 62 in the side plates 54 of said frame.

The operating mechanism for reciprocating the movable switch member includes a transverse operating shaft 64 which extends 25 between and is journaled at the reduced end portions 65 thereof in the opposite side plates 16 and 18, and a pair of operating toggles 66 which are disposed between and adjacent said side plates. The bottom plate 52 of frame 50 is provided with struck-out depending toggle 30 attaching ears 68 adjacent the side plates 16 and 18. Said toggles 66 are similar. Each toggle comprises a generally vertical toggle link 70 which is pivotally connected at its upper end 35 to a depending ear 68 of said frame by a shoulder rivet 72, and a lower toggle link 74 which is pivoted at one end to the lower end of said upper link by a shoulder rivet 76 and which is rigidly carried at its other end by 40 the operating shaft. Said shaft between the side plates 16 and 18 is square in section thus to provide opposed shoulders 78 which abut against the inner faces of said side plates 16 and 18 and prevent axial displacement of the 45 shaft.

The manner of fixing the lower toggle links 74 to the operating shaft 64 is especially simple and effective and constitutes an important feature of the invention. Said links are adapted to be secured to the shaft 64 so as to lie in spaced parallel planes which are perpendicular to the longitudinal axis of said shaft. To this end the square section of said shaft is provided with a diametric 55 passage 80 at each end, adjacent the shoulders 78, which passages are normal to a pair of opposed flat faces of the shaft. Each toggle link 74 preferably is stamped from sheet metal and is formed with a pair of side-by-side 60 rectangular marginal notches 82 at its free end and a prong or tongue 84 of rectangular section between said notches. The link is located on the shaft with the square portion of the shaft in the notches and the tongue in 65 the passage 80 of the shaft. The shaft fits

closely in the notches so that it is in effect keyed to the link. The tongue is longer than the thickness of the shaft so that it extends through and beyond the shaft. The extended end of said tongue is peened, or struck over, thus to fix the link rigidly to the shaft, the tongue 84 not only maintaining the link in position normal to the shaft but also preventing the displacement of the link axially of the shaft. It will thus be evident that the lower toggle links 74 constitute crank arms which are fixed to said operating shaft. Said lower toggle links are also provided with flat faces 86 which in the closed position of the mechanism, in which the toggle links are in a slightly overshot position, are adapted to engage the rod 29 carried by the adjacent side walls of the switch to limit the movement of the mechanism in a switch closing direction. The switch is limited in its movement in a switch opening direction by engagement of the bottom 52 of frame 50 with the upper ends of flanges 26.

The mechanism is constantly biased toward a toggle collapsed position by a pair of tensile 90 springs 90 which at their lower ends are connected eccentrically with the operating shaft adjacent the toggles 66 by a cotter pin 92 which extends through the shaft and at their upper ends to the toggle links 70 by cotter 95 pins 94 which extend therethrough. The springs are so arranged that, when the switch is closed, they hold the toggles in slightly overshot position against the stop rod 29 and, when the toggles are moved over their centers 100 in a switch opening direction, the springs act to collapse the toggles.

The operating shaft may be rotated by suitable external means as the key 96 which extends through an aperture 98 in a side wall 105 of the casing 10, and which is received on the cylindrical extended end portion 65 of the operating shaft 64. Said key is loosely connected with the shaft by a spring pin 102 which extends through the sleeve of said key 110 and through an aperture of said shaft. Said pin is received in an elongated slot 104 in the sleeve of said key whereby to provide a lost motion connection between the key and the shaft. The arrangement is such that a rotary movement of the key serves to rotate the operating shaft to move the toggles into over-center and switch closed position against the stop 29. Rotation of the key in the opposite direction moves the toggles over on-center position in a switch opening direction after which the toggles under the action of springs 90 move into a switch open position independently of further movement of the key. 125 A U-shaped guard plate 106 is provided about the key, external of the casing, to prevent it from accidental operation.

Thermal overload relays 108 are provided on said panel 28 which are connected by 130

means of rigid conducting straps 110 with the phase circuits of the switch.

The above described operating mechanism is simple and inexpensive to manufacture, being largely composed of cheap stampings, and is further advantageous in that it may be quickly assembled so that the ultimate cost of the switch is greatly reduced over the mechanism usually employed.

10 The electrical characteristics of the switch are such that but a relatively small amount of clearance is needed between the separable contact members when the switch is open. Thus the crank links 74 need have but a relatively short throw so that the pivotal connections between them and said long links 70 can be close to the shaft, thereby simplifying the construction, saving space, and improving the mechanical operation of the switch. This feature permits the switch to be opened and closed with little side throw on the sliding frame 52 since there is little change in angular position of the long links 70 in moving between open and closed positions.

25 Various changes in the construction and arrangement of the parts can be made without departing from the scope of the invention.

30 I claim:

1. An electric switch comprising the combination of cooperating stationary and movable switch members, and operating mechanism for said movable switch member including an operating shaft having a rectangular portion provided with a passage therethrough, a toggle arm comprising a flat plate having a rectangular notch in one end in which the squared portion of said operating shaft is received closely and having an integral prong which is located in the passage in said shaft, and means including a link pivotally connecting said arm and movable switch member.

40 2. An electric switch comprising the combination of cooperating stationary and movable switch members, and operating mechanism for said movable switch member including an operating shaft having a rectangular portion intermediate its ends provided with a transverse passage therethrough, a toggle arm formed with a rectangular notch in one end thereof in which the rectangular portion of said shaft is closely received, said arm also having an integral prong which extends into said notch and which is closely received in and extends through and beyond the passage in said shaft and has a head at its end which engages said shaft and fixes said toggle arm rigidly to said shaft, and link mechanism interconnecting said toggle arm and movable switch member.

45 3. An electric switch having the combination of cooperating stationary and movable switch members, a rotatable operating shaft

having a rectangular portion provided with a transverse passage therethrough, an operating toggle connecting said shaft with said movable switch member including a toggle arm comprising a flat link having two parallel closely spaced rectangular recesses in one end thereof in which the rectangular portion of said operating shaft is adapted to be closely received with the material between said recesses occupying the passage through said shaft, and a link pivotally connecting said arm and movable switch member.

50 4. An electric switch having the combination of cooperating stationary and movable switch members, a rotatable operating shaft having a rectangular portion intermediate its ends provided with a transverse passage therethrough, and an operating toggle connecting said shaft with said movable switch member including a toggle arm comprising a flat link having two parallel closely spaced rectangular recesses in one end in which the rectangular portion of said shaft is closely received and an integral prong between said recesses received within the passage in and extended beyond said shaft and having a projecting head that engages said shaft and holds said arm fixedly thereto.

55 5. An electric switch having a supporting frame including spaced side plates, a stationary contact supporting plate extended between and fixed to the upper ends of said side plates, contact members carried thereby, a movable contact carrying plate located between said side plates beneath said stationary plate, contact members carried thereby, a supporting frame for said movable contact plate located between and guided for vertical movement by said side plates, operating toggles located between and adjacent said side plates including upper toggle links having pivotal connections with the opposite ends of said frame, a transverse operating shaft of rectangular section extended between and having end bearing portions which are journaled in said side plates, lower toggle links having rectangular recesses at their lower ends in which said rectangular shaft is adapted to be closely received and also having integral prongs which extend into said recesses and through passages in said shaft and which are provided with struck-over extreme end portions which overlie said passages, whereby to secure said links fixedly to said shaft, and means to rotate said shaft in opposite directions.

60 6. An electric switch having stationary and movable contact members, and operating mechanism therefor including a movable operating frame having depending toggle attaching ears, a pair of spaced operating toggles having upper pivotal connections with the ears of said frame, a transverse operating shaft having a rectangular section provided with passages therethrough, said toggles hav-

ing recesses in their lower ends adapted to receive the rectangular section of said shaft closely therein and also having prongs which are received in and closely conform to the 5 passages through said shaft, said prongs terminating in struck-over end portions which overlie said passages whereby to lock said shaft fixedly in said recesses.

7. An electric switch having stationary and 10 movable contact members, and operating mechanism therefor including a vertically reciprocable frame having a depending toggle attaching member, an operating toggle having a pivotal connection at its upper end with 15 said attaching member, a rotatable operating shaft having a rectangular portion provided with a rectangular passage therethrough, said lower toggle link constituting a flat link of sheet metal formed with a rectangular recess 20 in its end having an intermediate rectangular prong extended thereinto, said recess adapted to receive the rectangular portion of said shaft closely therein with the prong of said toggle disposed within and extended 25 outwardly beyond said passage, said prong having its extended end struck-over and overlying said passage to secure said lower toggle link fixedly to said shaft.

8. Operating mechanism for an electric 30 switch including a rotatable operating shaft having spaced bearing portions and adjacent operating portions formed with flat angularly related peripheral faces, a flat link having a marginal recess therein the edges of which 35 conform with at least two of the angularly related faces of said shaft, means integral with said link arranged to hold said link and shaft fixedly in the aforesaid relation, and mechanism operated by said link.

40 9. In an electric switch the combination 40 of a supporting frame including a pair of spaced side plates, a contact supporting plate fixed to said plates at the tops thereof, contact members carried by the lower face of 45 said plate, a movable contact supporting plate located between said side plates, contact members carried by said movable plate arranged to cooperate with said stationary 50 contact members to complete the circuit 50 through the switch, operating mechanism including a supporting frame for said movable contact supporting plate which is guided for vertical movement between said side plates, an operating shaft extended transversely be- 55 tween said side plates and journalled at its ends in said plates and having an intermediate rectangular portion, a toggle arm comprising a flat plate having a marginal recess in which said rectangular portion is closely 60 received and having a prong projecting into said recess and in the plane of said arm which is received in and projects through a passage in said shaft, said prong adapted to be upset at its projecting end to fix said arm rigidly 65 to said shaft, operating means carried by

said shaft having a lost motion connection therewith, a toggle link connecting the extended end of said toggle arm pivotally with said frame, and a tensile spring connecting said toggle link and shaft whereby to bias 70 said toggle and movable plate toward switch open position.

10. In an electric switch the combination of a supporting frame including a pair of spaced side plates, a contact supporting plate 75 fixed to said plates at the tops thereof, contact members carried by the lower face of said plate, a movable contact supporting plate located between said side plates, contact members carried by said movable plate 80 arranged to cooperate with said stationary contact members to complete the circuit through the switch, operating mechanism including a supporting frame for said movable contact supporting plate which is guided for vertical movement between said side plates, an operating shaft extended transversely between said side plates and journalled at its 85 ends in said plates and having an intermediate rectangular portion, a pair of similar operating toggles located alongside said side plates each including toggle arms having marginal recesses at similar ends thereof which are adapted to receive the rectangular portion of said operating shaft and also having integral tongues extended into said recesses which are extended through and beyond transverse passages in said operating shaft, said tongues being struck-over at their 90 extended ends whereby to fix said toggle arms 95 rigidly to said shaft, said operating toggles having pivotal connections at their upper ends with said frame, tensile springs connected between said shaft and points intermediate said toggles constantly biasing said 100 toggles in a switch opening direction, means carried by said side frames arranged to engage said toggle arms in an overshot switch closed position thereof, and manual operating means having a lost motion connection 105 with said operating shaft for moving said toggles overcenter, whereby to open the 110 switch.

11. In an electric switch the combination of a pair of spaced side plates, a stationary 115 contact supporting plate connecting said plates at their upper ends, a movable contact supporting plate located between said side plates, a frame in which said movable plate is removably secured arranged to cooperate 120 with said side plates to guide said plate for vertical movement, operating mechanism for reciprocating said frame including a horizontal operating shaft journalled in said side plates beneath said frame and having two spaced relatively short toggle arms fixed thereto which are movable by the rotation of said shaft between a horizontal and a vertical position, and a pair of relatively long 125 and generally vertical toggle links separately 130

pivotaly connected at their lower ends to the free ends of said arms and at their upper ends to said frame.

12. An electric switch comprising stationary and movable contact members, an operating mechanism for the movable contact member including a crank arm having a non-circular slot therein which is open at one edge of said arm, a correspondingly non-circular crank shaft located in said opening, means integral with said arm which is located in a depression of said shaft and which holds said arm onto said shaft against detachment therefrom and which also holds said arm against axial movement along said shaft, and means operatively connecting said crank arm with said movable switch member.

13. An electric switch comprising stationary and movable contact members, an operating mechanism for the movable contact member including a crank arm having a non-circular slot therein which is open at one edge of said arm, a correspondingly non-circular crank shaft located in said opening, means integral with said arm which is located in a depression of said shaft and which holds said arm onto said shaft against detachment therefrom and which also holds said arm against axial movement along said shaft, means operatively connecting said crank arm with said movable switch member, and means located on opposite sides of said crank shaft providing abutments which are engaged by different parts of said crank arm to limit its movement in opposite directions.

14. An electric switch having stationary contact members, cooperating movable contact members, and switch operating mechanism including an operating shaft, a crank arm fixed to said shaft and extended laterally in one direction therefrom, means including a link pivotally connected with said extended end of said crank arm and also with said movable contact member, said link and said crank arm constituting a switch closing toggle member, and means for holding said toggle in set position and also for collapsing said toggle including a tensile spring one end of which is connected to an intermediate part of said link and the other end of which has a connection with said shaft on the same side thereof from which said crank arm extends.

15. An electric switch comprising stationary contact members, movable contact members, a movable horizontal supporting frame for said movable contact members, switch operating mechanism including an operating shaft which is extended horizontally beneath said movable frame, axially spaced crank arms fixed to said shaft and extended laterally therefrom in the same direction, vertically disposed links pivoted to the extended ends of said arms and having pivotal connections with spaced parts of said operating

frame, said links and crank arms constituting operating toggles, and means to hold said toggles in set position when the switch is closed and also to collapse said toggles when the switch is open including tensile springs which have their upper ends connected to intermediate parts of said links and their lower ends connected to said operating shaft between said crank arms and in positions which are spaced from said crank arms.

In testimony whereof, I have signed my name to this specification.

HENRY P. PINKHAM.
